BENDING BRAKE HAVING UNITARY ACTUATING MEANS FOR CLAMPING AND BENDING SHEET METAL

Peter Kilham, Attleboro, Mass.

Application March 23, 1944, Serial No. 527,722

12 Claims. (Cl. 153—16)

1

My invention relates to an improvement in bending brakes and has for one purpose to provide an improved bending brake.

Another purpose is to provide a bending brake adapted for bending relatively small pieces of sheet metal.

Another purpose is to provide a bending brake in which by a single movement of a control member, the article to be bent is first positively gripped and thereafter bent.

Another purpose is to provide a bending brake which shall be compact and relatively small and light.

Another purpose is to provide a bending brake with improved means for adapting it to form parts with a plurality of bends.

Another purpose is to provide an improved bending brake in which the angle of the bend may be readily adjusted and controlled.

Another purpose is to provide a bending brake in which improved means are provided for gripping the material to be bent.

Another purpose is to provide improved means for actuating the bending brake.

Other purposes will appear from time to time throughout the course of the specification and claims.

I illustrate my invention more or less diagrammatically in the accompanying drawings wherein:

Figure 1 is a perspective view of one form of the brake;

Figure 2 is a plan view with parts in section;

Figure 3 is a modified form of brake side elevation and illustrating the application of power means for actuating the brake, the brake being illustrated in open position;

Figure 4 is a view of the structure shown in Figure 3 illustrating the brake in closed position, ready for the bending operation;

Figure 5 is a side elevation of the structure shown in Figures 3 and 4, with parts in vertical section; illustrating the structure after a piece of material has been bent;

Figure 6 is a front elevation of the structure shown in Figures 3 to 5;

Figure 7 is an opposite end elevation of the same structure;

Figure 8 is a section on the line 8—8 of Figure 2;

Figure 9 is a side elevation of a variant form of the device;

Figure 10 is a section on the line 10—10 of Figure 9;

Figure 11 is a side elevation of a variant form

2

of the device illustrating the brake in open position;

Figure 12 is a side elevation of the structure shown in Figure 11, with the material gripped;

Figure 13 is a side elevation of the same structure illustrating the device with the material bent;

Figure 14 is a detail;

Figure 15 is a side elevation illustrating a further modification;

Figure 16 is a side elevation of the structure shown in Figure 15 with parts in section, illustrating the position of the part when the material is gripped;

Figure 17 is a detail illustrating the bending operation;

Figure 18 is an end elevation with parts in vertical section;

Figure 19 is a detail;

Figure 20 is an enlarged section on the line 20—20 of Figure 19;

Figure 21 is an enlarged section on the line 21—21 of Figure 19;

Figure 22 illustrates a variant form in which a roller is opposed to the material to be bent;

Figures 23 to 27 illustrate various stages of operations in bending, when a roller is employed both to hold the material and to bend it;

Figure 28 is a side elevation of a further variation;

Figure 29 is a detail of the structure shown in Figure 28;

Figure 30 is a partial side elevation illustrating a variant form of clamp;

Figures 31 and 32 illustrate the parts shown in Figure 30, in different positions;

Figure 33 is a partial end elevation of the structure in the position shown in Figure 31;

Figures 34 and 35 are partial side elevations illustrating a variant form in different positions;

Figure 36 is a front elevation, with parts broken away, illustrating the structure as shown in Figure 34;

Like parts are indicated by like figures throughout the specification and drawings.

Referring first to Figure 1, 1 illustrates a base. 2 illustrates a manually operated handle secured to the shaft 14 which may be journaled in any suitable manner in the side portions of the base 1. It will be observed as in Figure 1, that the base 1 has a flat top as shown at 1a.

Mounted on and movable with shaft 14 and keyed to it by any suitable key 56 is the cam lever 3 which may be secured, for example, by any

suitable bolt 15. It will be noted that there are identical cam levers at each side of the frame 1, on opposite ends of the shaft 14. The cam levers are actuated in unison by the handle 2, which rotates the shaft 14 and thus moves the cam levers. 21 is an upper rear shaft connected by eye links 39 to a forward shaft 29, the squared ends of which are mounted in horizontal slots in the upwardly extending brackets 16 which are secured to the sides of the base 1. Spacing collars 31 are placed between the upwardly extending brackets 16 and the links 39. A limited movement of the end of the shaft 29 is permitted in the slots, the shaft being centered between compressed springs 33, and adjustable set screws 32. A is a clamp member, having the arm 22 which is rotatable about the shaft 21, at its rear end.

23 are rollers or discs which engage the upper sides of the cam members 3. One of the cam members is provided with an indicating scale 19 across which passes the indicating finger 20 secured about the end of the shaft 21 and held in position for example by the bolt or screw 55. The rear end of the arm 22 of the member A is split and passes about the shaft 21 and may be held together for example by any suitable screw 24. The clamp member A is also connected to the shaft 29 by the eye bolt 27 with its upwardly extending screw threaded end 27a, which passes through arm 22 and receives the locking member 28. The flat top 1a of the base 1 is provided at its forward edge with an abutment insert 39 adapted to receive the clamping member 25 which is removably secured to the forward end of the clamp element, as by screws 26. The clamping member 25 is provided with the window 25a. 34 indicates an adjusting slide extending longitudinally along the flat upper surface 1a of the base 1. It may be more or less recessed in the upper surface. Its endwise movement is controlled by a locking bar 37, one end of which is held by a bolt 42, the opposite end being drawn downwardly against the upper surface of the bar 34 by the locking member 38. At its forward end the member 34 carries a transversely extending bar 34a which has an upper locking bar or abutment 35 secured thereto by any suitable screws or bolts 35a. It may receive and hold any suitable abutment member 36, the position of which may be adjusted to receive and engage the work X. It will be understood that a wide variety of members 36 may be employed, that if desired several may be simultaneously employed. They are readily removable by releasing the screws 35a. Thus I provide ready means for providing abutments to limit the inward movement of work of a wide variety of sizes and shapes.

Pivoted adjacent the forward end of the base, I illustrate bending levers 5. I illustrate them for example as pivoted to the sides of the base 1 upon any suitable bolts 9. Extending between the members 5 is the upper roller member 6 which may be rotatable about a shaft 12. 7 illustrates a connecting rod extending between the members 5. The members 5 are actuated in response to movement of the levers 3 by any suitable links 4 pivotally secured against abutment 10 by bolts 11 at their forward end and pivoted to the members 3 by bolts 13 at their rear end. It must be understood that in response to a forward movement of the handle 2 toward the front edge of the base the clamping member A will be forwardly and downwardly tilted about the shaft 29 by the camming action of the members 3. Thus the clamping abutment 25 will be moved

downwardly against the receiving abutment 39 to clamp the work X. Also, the members 5 will be upwardly rotated about their axis at 9 and the roller 6 will engage the lower face of the work X and bend it upwardly. The arc of the bend may be limited or controlled by adjustment of the set screw 18 by its locking nut 17. The upper end 18a of the set screw receives and serves as a limit for the downward movement of the portion 5a of the roller lever or bending lever 5. In Figure 1 the parts are shown with the abutment 25 in clamping position, but prior to the upward bending movement of the roller 6 against the bottom face of the work X. The shaft 29 is the pivot about which the clamping structure, and the axis of rotation can be adjusted toward and away from the forward edge of the member 39 by rotating the set screw or adjusting screw 32. I have illustrated in Figure 8 a roller or ball bearing support for the roller 6 about the shaft 12, antifrictional members 41 being indicated. It will be understood, however, that under some circumstances I may dispense with the roller bearings and rely on the rounded surface of the roller itself. However, I find some such antifrictional means as are shown in Figure 8 to be advantageous. I may vary the means for supporting the levers 5 on the base 1, but I illustrate any suitable means 40 as shown for example in Figure 2. I may also space the links 4 outwardly from the cam levers 3 by any suitable spacing sleeve 43 which receives the screws or bolts 13.

In Figure 3, I illustrate a minor modification of the device, in which the shaft 14 may selectively be operated by the manual control 2 or by hydraulic or pneumatic actuating means including a cylinder a with a fluid supply pipe b controlled by any suitable valve c. d indicates a piston operating through the rod e pivoted as at f to the lever g secured against rotation in relation to the shaft 14. h is a spring which tends normally to return the piston d to the initial position in which it is shown in Figure 3.

Figure 3 illustrates the structure in its initial position prior to a movement of the camming levers 3.

Figure 4 illustrates the structure at the time the abutment 25 has engaged the work X.

Figure 5 illustrates the same structure after the roller 6 has passed upwardly about the end of the abutment 25, and the end portion 5a of the roller carrying members 5 has engaged the upper end 18a of the set screw 18. The sequence of movements shown in Figures 3 to 5 applies also to the structure of Figures 1 and 2.

In the form of Figures 3 to 7, I illustrate a variant form of base in which a vertical pillar 45 rests upon or is secured to a relatively flat base 46 which may be provided with downward supports 46a of rubber or the like. Another variant is the use of a take up spring 23a on the screw threaded portion 27a of eye bolt 27, the upper end of said spring abutting the underside of arm 22, while the lower end rests on a shoulder formed on the eye portion of said bolt 27.

In Figure 9, I illustrate some variations in proportion which are in some circumstances advantageous and also provide for controlling the movement of the parts. The forward roller carrying levers 5 are connected to the levers 3 by links 62 having a rear end slightly downwardly curved as at 63. 61 are apertures in the levers 3 which make it possible to change the leverage of the link 62, thus enabling the operator to bend heavier

stock if such heavy stock is not bent to an acute angle.

Figure 10 indicates any suitable spacing support 43 extending outwardly from the lever 3 and adapted to receive the end of the link 62.

Referring to Figures 11 to 13, I illustrate a variant form of device in which I employ side members 50 through which passes a shaft 51 to which the cam levers 52 are secured. Pivoted as at 53 to the cam levers are a plurality of forwardly diverging links. The lower link 54 is pivoted to a lower portion of the roller lever 55. The upper link 56 has an upwardly curved forward end 57 to which is pivoted as at 58 an extension 59. 64 is an actuating arm secured to the cam lever 52 as at 65 and is provided with a pivoted handle element 66. It will be understood that when the user draws forward on the handle member 66 starting at the position in which the parts are shown in Figure 11, the camming levers 52 may be rotated initially to the position in which they are shown in Figure 12. The above described clamping structure is moved to the clamping position against work X, and the roller levers 55 have been slightly upwardly moved, if at all, toward the bottom of the work. Thereafter, as the user continues to draw forwardly on the handle 66, the roller levers 55 are moved upwardly into the position in which they are shown in Figure 13 and the work engaging member 67 rolls the work about the clamp as shown in Figure 13. The upward movement of the link 57 rotates the link 59 and thus rotates the member 61. The member 61 is shown in perspective in Figure 14 and constitutes a species of rocker roller.

Referring to the form shown in Figures 15 and following, I illustrate a motor driven structure, having however, the same general operative characteristics as regard to the movement of the clamp and the bending roller structure. For example, referring to Figure 15, 90 indicates a motor which may for example be an electric motor driving a worm 89 in mesh with the gear 88 on a shaft 14c. The shaft 14c is suitably journaled in the frame 1c. I illustrate, for example, a flat supporting base 92. Mounted for unitary movement with the shaft 14c is the cam 74 which is opposed to the roller 68 on the shaft 86. The brake clamp C is secured to the shaft 86 and extends forwardly therefrom and carries the bending blade 25c movably secured by bolts 26c, the blade being opposed to the forward edge abutment 39c upon which the work X may be positioned. The details of adjustment of the abutment for the work may be the same as in the earlier drawings and need not be separately described. The flat end of the shaft 29c passes through slots in the upwardly extending brackets 85 and the adjustment of the shaft is the same as in the earlier described forms.

83 indicates a roller supporting lever of which one end is mounted at each side of the base 1c as at 9c. The lever 83 carries rollers 80, 81 and 82. It is also provided with a pointer 91a opposed to the arcuate calibration 91 secured to the side of the frame 1c. The cam 74 actuates the levers 83 in the following manner. A rod 76 is pivoted at 87 to the cam 74 and is connected by a turnbuckle structure 77, 78 and 79 with a rod 96 which is pivoted as at 11c to the lever 83. The rod is thus adjustable as to length. I provide slotted member 75 along which the pivot structure 87 for the rod 76 may be adjusted toward and away from the axis of rotation of the cam 74. When the parts are in the position in which they

are shown in Figures 15, 16 and 17, the motor 90 may be employed to rotate the cam 74. Referring to the position in which the parts are shown in Figure 15, it shows the bending blade 25c in its most withdrawn position, leaving ample room for the work X to be inserted or removed. When the motor is rotated to rotate the cam 74, the roller 68 is raised and the clamp structure is rotated about the center of the shaft 29c. The result is to move the blade 25c down into clamping relationship against the fixed abutment 39c and the work X, which is the position of the parts as shown in Figure 16. When the rotation has continued to the position shown in Figure 17, the lever 83 continues its rotation and the roller 80 is effective to bend the work X as shown. The angle of the bend may be checked by watching the relationship between the pointer 91a and the calibration 91. It will be understood that any suitable anti-frictional means 97 and 98 may be used for supporting the rollers 80 and 81 as shown in Figures 20 and 21. I may find it advantageous to form the rollers 68 with flanges as shown in Figure 18. 99 is a bearing and spacing sleeve for the pivot 87 and 100 and 101 are anti-friction bearing members for the shaft 14c.

With reference to Figures 22 to 27, I may vary the structures shown by employing, with any one of the forms of my device herein shown, 30 a clamping member 93 which, instead of terminating with a blade edge, carries a roller 94 journaled as at 95 in bearing arms 93a, shown in Figure 22. The work is therefore, gripped not by a fixed blade, but by a roller, or a member having a cylindrical exterior. When the bending roller 80 is moved upwardly against the bottom of the work X, it is effective, as shown in Figure 24, to bend the work in order to form a partly cylindrical edge portion. This cylindrical edge portion may then be engaged with the roller 94, as shown in Figure 25 and the work can be wrapped around the roller 94 (see Figs. 26 and 27). It is possible in this fashion to roll substantially complete tubes.

45 Referring to Figures 28 and 29, I may apply to the clamp structure in Figure 16 a somewhat different bending blade. I illustrate, for example, a blade structure 103 terminating in a generally vertical portion 103a and having angular lower faces 103b. The abutment 39 is removed and replaced by an abutment 104 having a channel 104a in its upper face. The abutment being secured for example by bolts or screws 105. The connecting rod structures 76, 96 may then be moved into inoperative position, by moving the pivot 87 toward the center of the shaft 14c, as shown in Figure 28. The cam 74, when rotated, is then effective to actuate the clamp structure 84, but has no effect on the position of the roller 80. The bending blade 103a is then moved downwardly toward the fixed abutment 104 and is adjusted to align with the depression 104a. The downward movement of the bending blade 103a may be limited by adjustment of the nut 28 on the screw 27a to provide any desired angle of bend, within a substantial range. The sharp edge between the faces 103b provide a small radius bend and the intermediate portion of the work X is forced down into the depression 104a to produce the desired form. The shaft 29c may be adjusted in the slot in the bracket 85 suitably to align the blade 103a with the depression 104a.

Referring to Figures 30 and following, I illustrate the application of my structure to shearing and forming sheet metal. It will be under-

stood that the brake structure proper may be the same as shown in Figure 28. However, I provide a somewhat different type of abutment 120, which has a vertical rearward face 121 and a flat top 122 somewhat above the top level of the base of the brake. Removably secured to the brake bar 84 is the shearing blade 123, 123 is a spring hold down which may be unitarily secured with the shearing member 123 to the bar 84, as by any suitable bolts or screws 125. When the work X is in position, and the brake structure is actuated, the shearing member and the spring are at first out of contact and above the work as shown in Figure 30. Thereafter, as shown in Figure 31, the hold down spring 124 engages the work X and holds it in position during the shearing operation. In Figure 32 the shear is illustrated. As shown in Figure 33 a plurality of hold down springs 124 may be employed with a single shearing blade 12.

A further variation illustrated in Figures 34 and following employs spaced rollers on the base to assist in bending or forming material. Referring first to Figure 34, I illustrate a preferably removable bracket structure 139 mounted on the brake base and carrying two rollers 131 and 132 which are spaced apart sufficiently to provide room for the entry therebetween of a bending blade 133 which may have a rounded lower edge or end portion 134. In Figure 35 the parts are shown in initial position and in Figure 34 in bend forming position.

Figures 34 and 36 illustrate the bending of a relatively short piece of work X but it will be understood that longer pieces may be bent, or a plurality of pieces. No separate clamping means are employed or needed.

It will be realized that whereas I have described and shown a practical and operative device, nevertheless many changes may be made in size, shape, number and disposition of parts without departing from the spirit of my invention. I, therefore, wish my description and drawings to be taken as in a broad sense illustrative or diagrammatic. It will be understood that the proportion of the parts may be widely varied and that a wide variety of accessories may be provided. For instance, in connection with the basic brake or clamp which is shown in all forms described herein, I illustrate various bending blades or forming members which may be removably applied to the front end of the clamp. I have also illustrated various work receiving abutments adapted for clamping, bending and shearing. I may employ any suitable means for driving the device. I have illustrated a motor in Figures 15 to 18 and a hydraulic or pneumatic means in Figures 3 to 8. I may employ hand means either in the place of or in addition to the power means, in order to actuate the device, and I illustrate a variety of hand means such as the simple lever 2 of Figure 1 and the pivoted structure 64, 66 of Figures 11 and 13.

The use and operation of the invention are as follows:

Basically, I provide a relatively small, relatively simple brake. It may be made in larger sizes, but one advantage of my design is that it may be made in small sizes and will work with high efficiency, and is easily operated with a minimum output of energy. The clamp structure proper forms a species of truss pivoted intermediate its end. The various cam structures shown, for example the levers 3 or the cam rollers 74, are effected to raise the rear end of the brake bar

or clamp bar structure, thus forcing the forward end down into clamping or forming relationship with the work. I find it advantageous to provide unitary means for actuating the bending structure from the same power source, in proper timed relationship to the effective clamping of the work. In the various forms herein shown the main drive shaft 14, 14c or 51, whether manually actuated or power actuated, performs the two-fold function of camming up one end of the brake or clamp structure to depress the opposite end, and thereafter actuating the bending structure or roller to bend the clamped work. However, as shown in Figures 15, 16, 17 and 28, I can provide means for interrupting the effective driving connection between the power shaft 14c and the roller actuating levers 83, while continuing the effective drive of the clamping bar itself. This is advantageous when the device is employed for forming or bending by forcing the work into a depression, as shown in Figure 28, or when the device is used for shearing as shown in Figures 30 to 32. It is not necessary to interrupt the roller actuating means, although such may be done if one wishes to, because the movement of the clamping beam or bar is complete in all cases before the roller moves above the level of the table.

By employing adjustable abutments such as 30 are shown at 34, 35 and 36, I may employ my brake to bend a variety of sizes and forms of material. I may form a sharp bend as shown for example in Figure 13, and a bend the angle of which can be strictly controlled, as by actuating the set screw 18 shown in various drawings. On the other hand, where I wish a rounded bend or a rounding or rolling of the material, I may employ the clamping roller 94 as shown in Figures 22 and following and may roll the material. I have therefore provided a structure having great flexibility which may be applied to a wide variety of work and which may easily be operated by a single operator and may economically be employed to bend relatively small pieces, or pluralities of small pieces.

An important advantage of my device is the fact that the clamping bar or beam A, and the abutment members or clamp elements proper, such as 25 of Figure 9, are so related to the rest 50 of the machine that a box or member can be bent, in which the side of the box or the length of the piece exceeds the width of the brake. In my brake there are no projecting hinges or other obstructions which limit the size of the piece to be worked on. Also since there is no interference with the piece undergoing bending, a small section of a long piece can be bent, and a piece may be bent even though it has laterally extending parts which give the piece as a whole a width 55 greater than the width of the brake, or of the work engaging parts of the brake. A further advantage is that an angle of any length can be bent on my brake by bending a piece a bit at a time and moving the piece laterally between bending operations, to complete the bend in two or more separate movements.

I claim:

1. In a bending brake, a base, an abutment on said base, a bending member movably mounted 70 on said base adjacent said abutment, means for guiding said bending member along a path extending adjacent the edge of the base and passing upwardly above the level of said abutment, including a lever pivoted to the base, on 75 which the bending member is mounted, a clamp

structure pivoted on said base, intermediate the ends of the clamp structure, for rotation about a generally horizontal axis, said clamp structure including a portion adapted to be opposed to the work when the opposite end of the clamp structure is raised, and means for raising the opposite end of the clamp structure and for thereby rotating it about its axis and into clamping position, for thereafter moving said bending member upwardly toward and past the work, including a cam element mounted on said base and means for moving it, a camming connection between said cam element and said clamp structure, and an actuating connection between said cam element and said bending member, and means for rendering the connection between the cam element and the bending member ineffective while maintaining the camming connection between the cam element and the clamp structure.

2. In a bending brake, a base having a generally horizontal upper face with a free, accessible forward edge, a work abutment adjacent and spaced inwardly from said free edge, adapted to receive, in gauging relationship, an inner portion of the work manually positioned thereagainst, a clamp structure pivoted on and overlying said base and including a portion adapted to be opposed to the work at an area adjacent said free edge, a bending member movably mounted on said base, and unitary means for first moving said clamp structure downwardly against the work, and for thereafter moving said bending member upwardly toward the lower face of the work along a path extending adjacent said free edge of the base and passing upwardly from below to a level above the clamping plane of said clamp structure against the work, including a cam lever rotatable on the base and means for rotating it, a link connection between said cam lever and the bending member and a cam connection between said cam lever and the clamp structure and gauge means intermediate said cam lever and clamp structure, including opposed members mounted respectively on the cam lever and the clamp structure.

3. In a bending brake, a base having a generally horizontal upper face with a free, accessible forward edge, a work abutment adjacent and spaced inwardly from said free edge, adapted to receive, in gauging relationship, an inner portion of the work manually positioned thereagainst, a clamp structure pivoted on and overlying said base and including a portion adapted to be opposed to the work at an area adjacent said free edge, a bending member movably mounted on said base, and unitary means for first moving said clamp structure downwardly against the work, and for thereafter moving said bending member upwardly toward the lower face of the work along a path extending adjacent said free edge of the base and passing upwardly from below to a level above the clamping plane of said clamp structure against the work, said bending member including a transversely extending work engaging element and a lever at each side of the base, said levers being rotatable about a common center, each said lever having an arm to which the work engaging element is secured, an arm to which said link connection is secured and an abutment arm.

4. In a bending and forming brake, a bed, clamping means mounted on said bed, including a clamping blade located adjacent the forward edge of said bed, gauging means on said bed for engaging the article to be bent, and bending

means, including a roller, means for initially positioning said roller at a level below the work to be bent and means for guiding said roller for movement upwardly against the work, the path described by the roller in its upward movement approaching closely adjacent the forward edge of the bed and clamping blade, the guiding means including a pair of T-shaped levers pivoted adjacent the forward edge of the bed, the roller being mounted on the upper end of the T-shaped levers, an actuating link connected to the lower end of the T-shaped levers and means for actuating it.

5. In a bending and forming brake, a bed, clamping means mounted on said bed, including a clamping blade located adjacent the forward edge of said bed, gauging means on said bed for engaging the article to be bent, and bending means, including a roll, means for initially positioning said roll at a level below the work to be bent and means for guiding said roller for movement upwardly against the work, the path described by the roller in its upward movement approaching closely adjacent the forward edge of the bed and the clamping blade, the guiding means including a pair of T-shaped levers pivoted adjacent the forward edge of the bed, the roller being mounted on the upper end of the T-shaped levers, an actuating link connected to the lower end of the T-shaped levers and means for actuating it, including a manually operable lever pivoted in relation to the bed and operatively connected to said linkage.

6. In a bending and forming brake, a bed, clamping means mounted on said bed, including a clamping blade located adjacent the forward edge of said bed, gauging means on said bed for engaging the article to be bent, and bending means, including a roller, means for initially positioning said roller at a level below the work to be bent and means for guiding said roller for movement upwardly against the work, the path described by the roller in its upward movement approaching closely adjacent the forward edge of the bed and the clamping blade, the guiding means including a pair of T-shaped levers pivoted adjacent the forward edge of the bed, the roller being mounted on the upper end of the T-shaped levers, an actuating link connected to the lower end of the T-shaped levers and means for actuating it, and adjustable means for limiting the upward movement of the roller.

7. In a bending and forming brake, a bed, clamping means mounted on said bed, including a clamping blade located adjacent the forward edge of said bed, gauging means on said bed for engaging the article to be bent, and bending means, including a roller, means for initially positioning said roller at a level below the work to be bent and means for guiding said roller for movement upwardly against the work, the path described by the roller in its upward movement approaching closely adjacent the forward edge of the bed and the clamping blade, the guiding means including a pair of T-shaped levers pivoted adjacent the forward edge of the bed, the roller being mounted on the upper end of the T-shaped levers, an actuating link connected to the lower end of the T-shaped levers and means for actuating it, and adjustable means for limiting the upward movement of the roller, including an extension on one of said levers, movable unitarily therewith, and an adjustable limit stop opposed thereto.

8. In a bending and forming brake, a gener-

ally horizontal bed having a free forward edge, a clamp blade and actuating means for moving it downwardly into clamping relation with said bed adjacent said forward edge, a bending roller and actuating means for moving it upwardly against the clamped work, and a unitary control mechanism adapted first to actuate the means for clamping the clamp blade and thereafter to actuate the means for moving the roller against the work, said mechanism including a manually operable actuating member, a connection between it and the clamp blade actuating means, and a connection between it and the roller actuating means, and additional power means for actuating the actuating member, including a cylinder and a piston and means for delivering a fluid to said cylinder.

9. In a bending and forming brake, a bed having a forward edge, a clamp blade and actuating means for moving it into clamping relation with said bed adjacent said forward edge, a bending roller and actuating means for moving it upwardly against the clamped work, and a unitary control mechanism adapted first to actuate the means for clamping the clamp blade and thereafter to actuate the means for moving the roller against the work, said mechanism including a hand lever, a connection between the hand lever and the clamp actuating means and a connection between the hand lever and the roller engaging means, and additional power means for actuating the hand lever including a cylinder and a piston, means for delivering fluid to the cylinder.

10. In a bending and forming brake, a generally horizontal bed having a free forward edge and an upper surface adapted to receive and support, adjacent said edge, the material to be bent, a clamping blade located adjacent the forward free edge of the bed, and movable downwardly and upwardly toward and away from the upper surface of the bed, an abutment member movable bodily along a generally upright path passing adjacent the free forward edge of the bed, and unitary actuating means adapted first to move the clamping blade downwardly into clamping position and thereafter to move the abutment member upwardly against the lower face of material clamped by the clamping blade, whereby that portion of the material which extends forwardly of the edge of the clamping blade is upwardly bent.

11. In a bending and forming brake, a generally horizontal bed having a free forward edge and an upper surface adapted to receive and support, adjacent said edge, the material to be bent, a clamping blade located adjacent the forward free edge of the bed, and movable downwardly and upwardly toward and away from the upper surface of the bed, an abutment member movable bodily along a generally upright path passing adjacent the free forward edge of the bed, and

unitary actuating means adapted first to move the clamping blade downwardly into clamping position and thereafter to move the abutment member upwardly against the lower face of material clamped by the clamping blade, whereby that portion of the material which extends forwardly of the edge of the clamping blade is upwardly bent and a manually operable actuating lever for said unitary actuating means.

12. In a bending and forming brake, a generally horizontal bed having a free forward edge and an upper surface adapted to receive and support, adjacent said edge, the material to be bent, a clamping blade located adjacent the forward free edge of the bed, a horizontal pivotal connection for said clamping blade remote from said free edge, a bending abutment and a movable support therefor including a lever pivoted in relation to said bed for rotation about a generally horizontal axis generally parallel with the free edge of the bed and with the axis of the blade and unitary means for first moving the blade into work gripping position in relation to the bed and for thereafter bending work gripped between the blade and bed, including a lever pivoted in relation to said bed, an actuating connection between said lever and said blade and an actuating connection between said lever and said movable support.

PETER KILHAM.
